UNITED STATES PATENT OFFICE

2,639,489

APPARATUS FOR MAKING BUCKLES

Everyl M. Torbert, Freeland, Md., assignor to
 Samuel Greenberg and Milton Kolker, a co-
 partnership doing business as Buckle-Craft Co.,
 Baltimore, Md.

Application January 28, 1948, Serial No. 4,850

1 Claim. (Cl. 29—3)

1 My invention consists in a new and useful improvement in apparatus for making buckles and is designed to provide a machine for stamping the bodies of the buckles, producing the tongues for the buckles, and applying the tongues to the bodies coincidentally with the stamping of the bodies. Prior to my invention, buckles were produced by performing a number of sequential, independent operations. The bodies were stamped in a punch press, the tongues were produced, and the tongues were attached to the bodies, by the functioning of entirely separated machines, requiring manual operations. Large scale, rapid mass production was rendered impossible by the necessary transfer of the work from and to the necessary machines, and by the manual operations required.

All of these objectionable features of the former production means are completely eliminated by my improved apparatus comprising a suitable punch press provided with the novel mechanisms embodying my invention. Actual experience with an apparatus, embodying my invention, which has produced over a million buckles, shows conclusively that my invention provides a machine capable of efficient, large scale, rapid, mass production of buckles. This improved apparatus fabricates the completed buckles in a continuous operation so long as it is supplied with the raw material comprising stock for the bodies of the buckles, in the form of a ribbon of suitable metal of suitable width and thickness, and stock for the tongues, in the form of wire stock of suitable metal of suitable gauge.

The particularly novel and useful features of my apparatus are the means for forming the bodies, the means for forming the tongues, the means for applying the tongues to the bodies, and the means for synchronizing all of said means to effect the continuous process of producing the completed buckles in an uninterrupted sequence of operations upon the raw material.

While I have illustrated in the drawings and have hereinafter fully described one specific embodiment of my invention, it is to be distinctly understood that I do not consider my invention to be limited to said specific embodiment but refer for its scope to the claim appended here-to.

In the drawings:

Fig. 1 is a front elevation, partly in section, the press being open.

Fig. 2 is a horizontal section on the line 2—2 of Fig. 1, in the direction of the arrows.

2 Fig. 3 is a horizontal section on the line 3—3 of Fig. 1, in the direction of the arrows.

Fig. 4 is a transverse, vertical section on the line 4—4 of Fig. 3, in the direction of the arrows.

Fig. 5 is a view similar to Fig. 4, the press being closed.

Fig. 6 is a horizontal section on the line 6—6 of Fig. 5, in the direction of the arrows.

Fig. 7 is an enlarged, vertical section on the line 7—7 of Fig. 3, in the direction of the arrows.

Fig. 8 is a view similar to Fig. 7, the parts being in the positions assumed when the press is closed.

Fig. 9 is an enlarged, vertical section on the line 9—9 of Fig. 1, in the direction of the arrows.

Fig. 10 is a fragmentary top plan of the metallic ribbon stock.

Fig. 11 is a fragmentary, vertical section on the line 11—11 of Fig. 1, in the direction of the arrows.

Fig. 12 is a greatly enlarged, horizontal section on the line 12—12 of Fig. 4, in the direction of the arrows.

Fig. 13 is a view similar to Fig. 12, on the line 13—13 of Fig. 5, in the direction of the arrows.

Fig. 14 is a view similar to Figs. 7 and 8, the parts being in the positions shown in Figs. 5 and 13.

As illustrated in the drawings, my improved apparatus has a fixed bed B and a vertically reciprocable presser head H slideable on guide pillars P, such as are common in punch presses. Suitable plates 1 and 2 are mounted on the bed B and the head H, respectively, by means of bolts 3 and 4, respectively. The plate 1 has a longitudinal axial channel 5 in which are mounted female dies 6 and 7, by means of bolts 8 and 9, respectively, and which have registering, longitudinal, axial passageways 10 and 11, respectively, for the stock S. The plate 2 has a longitudinal, axial channel 12 in which are mounted punch blocks 13 and 14 for co-action with the die 6, and a punch block 15 for co-action with the die 7. The block 13 has a pair of punches 16, 17 co-acting with bores 18, 19 in the die 6, which are suitably configured to punch the desired openings in the stock S for the bodies of the buckles. Suitable bores 20 and 21 are

provided in plate 1 and bed B, respectively, registering with bores 18 and 19 for the discharge of the punched-out material. The block 14 has a punch 22 co-acting with a socket 23 in the die 6, which are suitably configured to stamp the body of the buckle in the stock S. The block

55

15 has a punch 24 co-acting with a bore 25 in the die 1, which are suitably configured to punch the completed buckle from the stock S. Suitable bores 26 and 27 are provided in the plate 1 and the bed B, respectively, registering with bore 25 for discharge of the buckles from the apparatus to any suitable container therefor.

The above-described details of construction effect the production of the body of a tongueless buckle. I will now describe the details of construction of my novel apparatus which effect the production of the tongue and its application to the body, coincidentally with the production thereof.

The mechanism for forming the tongue and feeding it to the body of the buckle is mounted on a block 28 disposed on the plate 1 intermediate the dies 6 and 7 and seated in a socket 29 in the plate 1 (Figs. 1, 3 and 4). This block 28 has a cut-out portion 28-a and a thickened portion 30 which is suitably configured on its edge projecting from the body of the block 28 to form an anvil 31 (Figs. 7, 8 and 14). Suitably journaled in the block 28 there is a rock shaft 32 on which is mounted a rocker head 33 having abutments 33-a and 33-b engaging the bottom wall 29-a of the socket 29, to limit the degree of rocking movement of the rocker head 33. The rocker head 33 has a thickened portion 34 which is suitably configured on its edge projecting from the body of the rocker head 33 to form a hammer 35 to co-act with the anvil 31.

For a purpose presently to be explained, the anvil 31 (Fig. 7) has a concave portion 31-a concentric with the shaft 32 and a convex portion 31-b extending from the lower end of the portion 31-a to a rectilinear portion 31-c. The hammer 35 has a convex portion 35-a concentric with shaft 32 and on a radius substantially corresponding with the radius of the concave portion 31-a of the anvil 31, and a concave portion 35-b. Portions 35-a and 35-b are so relatively disposed that their junction provides a cutting edge 36. The hammer 35 has a cam surface 35-c below the portion 35-b.

For a purpose presently to be explained, the anvil 31 has a convex portion 31-d above the portion 31-a and merging upwardly into a concave portion 31-e. The hammer 35 has contiguous concave and convex portions 35-d and 35-e, corresponding to portions 31-d and 31-e, respectively, of the anvil 31. Corresponding concave portions 31-f and 35-f are provided on the upper ends of the anvil 31 and the hammer 35, respectively.

For operating the hammer 35, the rocker head 33 on which the hammer 35 is formed has a pin 37 on which is pivoted one end of a link 38 having its other end pivoted on a pin 39 tapped into a block 40 through which passes a vertical rod 41 fixed in the presser head H, depending therefrom and passing freely through the plate 1 and the bed B (Fig. 4). The rod 41 has a chamfered portion to provide a plane surface 42 against which bears the plane head 43 of a plunger 44 of suitable material slideable in a housing 45 tapped into the block 40 and having a cap 46 threaded on its outer end. An adjusting screw 47 with a head 47' is threaded in the cap 46 and bears on a coil spring 48 which bears on the bolt 44 to urge it against the rod 41. The rod 41 has a tubular housing 49 mounted on the block 40.

The mechanism for supplying the wire stock for the production of the tongues will now be described. A bracket 50 depends from the bed B and carries on its lower end a dove-tailed trackway 75

51 on which is vertically slideable a carriage 52 having a shim 53 with presser bolts 54 to effect frictional engagement of the carriage 52 and the trackway 51. The carriage 52 has formed integral therewith an L-shaped bracket 55 carrying an L-shaped plate 56 having a horizontal tongue 57 carrying a vertical bolt 58 passing through a slot 59 in a gripper plate 60 biased toward the tongue 57 by a coil spring 61 about the bolt 58 and adjustably tensioned by a nut 62 threaded on the bolt 58. The tongue 57 has an upstanding lug 63 in which is threaded an adjusting bolt 64 with a slotted head 65, bearing on the outer edge of the gripper plate 60. The plate 60 has an offset tongue 66. The gripper plate 60 is formed on its inner edge as a jaw 67 disposed obliquely to the vertical plane surface of the portion 68 of the plate 56. A guide tube 69 is mounted on the bracket 55 for guiding the wire stock W from the feeding mechanism to the mechanism for forming the tongues. The tube 69 has a reduced upper end portion 69-a slidably received in a tube 70 tapped into the bottom of the bed B. Suitable co-axial bores 70-a and 70-b are provided in the bed B and the plate 1, respectively, co-axially with the co-axial tubes 69 and 70, to permit passage of the wire stock W. The bracket 55 has a collar 71 through which passes the lower reduced threaded portion 72 of the rod 41 provided with sets of lock nuts 73 and 74 above the collar 71. Below the collar 71, the rod 41 has a further reduced portion 75 forming a peripheral abutment 76 at the lower end of the portion 72. A collar 77 about the portion 75 is urged against the abutment 76 by a coil spring 78 about the portion 75 and adjustably tensioned by a lock nut 79 threaded on the lower end of the portion 75.

The mechanism for attaching the tongue to the body of the buckle is mounted in the block 14 disposed in the channel 12 of the plate 2 on the presser head H (Figs. 1, 2, 4 and 11), and comprises a plunger 80 carrying a head 81 having a stud 82 and a semi-circular groove 83. The plunger 80 is slidably received in co-axial bores 14-a, 14-b and 14-c in the block 14, the plate 2 and the head H, respectively (Fig. 11). A coil spring 80-a about the plunger 80 is confined between the head H and a flange 80-b on the plunger 80 to bias the plunger 80 downwardly. The head 81 on the lower end of the plunger 80 extends through a bore 14-d in the block 14 and has a vertical key-way 81-a with which co-acts a key 81-b threaded in the block 14, to prevent rotatory movement of the head 81. The stud 82 is channeled on its transverse axis (Fig. 2) to provide an oblique shoulder 82-a (Fig. 14) merging upwardly into a vertical groove 82-b (Figs. 1 and 13) merging tangentially into the semi-circular groove 83 (Fig. 1).

For the purpose of frictionally engaging the stock S during its transit through the passageways 10 and 11 of the dies 6 and 7, there is provided a presser plate 84 (Figs. 3 and 4) slidably mounted in the dies 6 and 7 adjacent passageways 10 and 11 and urged by leaf springs 85 mounted in the dies 6 and 7, to bear against the stock S in the passageways 10 and 11.

For the purpose of properly relating the stock S to the mechanism for applying the tongue to the body, there is provided a traction device for automatic displacement of the stock S (Figs. 1, 2 and 9), comprising a housing 86 suitably mounted in plate 2 adjacent the block 15. A plunger 87 is vertically slideable in the housing 86 with a coil spring 88 biasing the plunger downwardly

and a pin 89 in a slot 90 in housing 86 to limit the sliding movement of the plunger 87. Pivoted on the lower end of the plunger 87 there is a pair of levers 91 connected by a loop 92 having an outer peripheral convex face 93. A coil spring 94 having one of its ends suitably fixed adjacent the housing 86 and its other end attached to one of the levers 91 serves to bias the loop 92 below the lower horizontal end 95 of the plunger 87. The die 7 in the plate 1 in the bed B (Figs. 1 and 3) has a socket 96 having a concave wall 97 corresponding in contour with the convex face 93 of the loop 92, and a bottom horizontal wall 98.

Operation

I will now describe the operation of my improved apparatus. The parts being in the positions shown in Fig. 1 (press open), the stock F, fed from a reel or any other suitable form of support, is inserted in the passageways 10 and 11 in the dies 6 and 7 for feed movement from left to right as viewed in Fig. 1. The head H is then depressed by any suitable means (not shown), thereby moving the parts to the positions shown in Figs. 5, 8, 13 and 14 (press closed). This downward movement of the head H causes punches 16 and 17 to pass through the stock S producing openings S-1 and S-2 therein (Fig. 10) which are so configured as to produce a bar S-3 for the body of the buckle having lateral, aligned notches S-4 for receiving the loop of tongue. The punch 22 stamps the stock S into the socket 23 to form the body S-5 of the buckle (Fig. 10). The punch 24 passes through the stock S to produce the orifice S-6 in the stock S (Fig. 10).

It will be noted (Fig. 1) that on this down stroke of the head H, the head 81 will contact the stock S since no opening in the stock S has as yet been made in vertical alignment with the head 81. When the head 81 contacts the stock S, relative movement of head H, plate 2 and head 81 is provided by compression of the spring 80-a (Fig. 11).

The head H is then elevated, removing the punches 16, 17 and 22 and 24 from the dies 6 and 7. By any suitable means (not shown), the elevation of the head H automatically advances the stock S one step from left to right (Fig. 1) so that the stock S is so disposed that its orifice S-6 is located in the socket 96 of the die 7. The head H is then depressed, which causes the plunger 87 to intrude the pivoted loop 92 into the socket 96 of the die 7 and into the orifice S-6 of the stock S disposed in the socket 96. When the plunger 87 is sufficiently depressed by the downward movement of the head H, its lower end 95 contacts the bottom 98 of the socket 96 causing the plunger 87 to be pressed against spring 88 and into its housing 86. The loop 92 rests on the bottom 98 of the socket 96 and levers 91 pivoting about plunger 87 cause the loop 92 to press its convex face 93 against the concave right wall S-7 of the orifice S-6 to move the stock to register wall S-7 with the concave wall 97 of the socket 96. This movement of the stock S, produced by the traction device as above described, disposes the openings S-1 and S-2 in the stock S, produced by the first down stroke of the head H as above described, in relation to the punch 22 and socket 23 for the stamping of the body S-5 of the buckle on the complete depression of the head H. It will be noted (Fig. 1) that the traction device functions to register the openings S-1 and S-2 and the punch 22 and the

socket 23 on the initiation of the down stroke of the head H, and that the punch 22 functions to stamp the body S-5 of the buckle on the completion of the down stroke of the head H.

5 The head H is then elevated, causing the advance of the stock S one step as above described, which disposes the body S-5 of the buckle below the head 81 as illustrated in Fig. 1.

With the stock S so disposed and the parts 10 as shown in Fig. 1 (press open), the wire stock W, fed from a reel or any other suitable form of support, is passed upwardly between the gripper jaw 67 and the plate 68 and through the guide tubes 69 and 70 so that its upper end is received 15 through the openings S-2 in the stock S and disposed between the anvil 31 and the hammer 35. During the above-described operations on the stock S caused by the reciprocation of the head H, the means for feeding the wire stock W and for forming tongues therefrom have been idling devoid of the wire stock W. When the wire stock W has been supplied to the feeding and forming means, as above described, the feeding and forming means begin to function on depression of the head H. This downward movement of the head H depresses the rod 41 which, due to the frictional engagement of the plunger 44, depresses the block 40 causing the link 38 to rock the rocker head 33. This movement of 20 the head 33 causes the cutting edge 36 on the hammer 35 to sever the wire stock W, thereby producing a portion W-1, which is precisely measured, to be formed into a tongue T. The co-acting anvil 31 and the hammer 35 form the 25 tongue T, their walls 31-d, 35-d and 31-e, 35-e producing reversely curved portions T-1 and T-2 (Fig. 8), and the anvil 31 and the hammer 35 co-act to grip the portion W-1. The down stroke of the head H which produces the tongue T, as 30 above described, causes the traction device to move the stock S to bring the bar S-3 which bounds the opening S-2 through which the portion W-1 of the wire stock W has been received, to bear against the portion W-1 received in one 35 of the notches S-4 in the bar S-3. It will be noted (Fig. 14) that the bar S-3 is disposed precisely above the vertically disposed wire stock W and symmetrically above the concave portions 31-f and 35-f of the anvil 31 and the hammer 35, and that the stud 82 passes through opening 50 S-2, into the cut-out portion 28-a of the block 28, and against the hammer 35. Further depression of the head H imposes the head 81 on the upper end of the portion W-1 which is received against the shoulder 82-a and guided into the groove 82-b of the stud 82. Sufficient pressure is exerted by the head 81 upon the completion of the down stroke of the head H to form the upper end portion W-1 into an annulus T-3 received in the semi-circular groove 83 and the concave portions 31-f and 35-f of the anvil 31 and the hammer 35, respectively, disposed circumferentially of the bar S-3 and seated rotatively in the notches S-4, thus completing the 55 forming of the tongue T and its application to the body S-5 of the buckle.

When the anvil 31 and the hammer 35 co-act to form the tongue T, as above described, the surface 35-c of the hammer 35 cams the wire stock W against the portion 31-c of the anvil 31, and the co-acting portions 31-b and 35-b of the anvil 31 and the hammer 35, respectively, engaging the upper cut end of the wire stock W produce the curved portion W-2. The movement 60 of the head 33 to effect the severing and form-

ing of the portion W-1, as above described, is limited by the engagement of the abutment 33-b on the head 33 with the wall 29-a of the socket 29, and through the link 38 the movement of the block 40 is arrested. Due to the frictional engagement of the plunger 44 with the plane surface 42 of the rod 41, the further depression of the rod 41 exerts tension through the link 38 to cause the portion W-2 to be gripped between the anvil 31 and the hammer 35, during the further depression of the rod 41 moving through the block 40. When the depression of the rod 41 brings the lock nuts 74 into engagement with the collar 71, the carriage 52 is moved downwardly on its trackway 51 thereby moving the gripper jaw 67 and the plate 68 downwardly along the wire stock W which is immobilized by reason of the gripping action of the co-acting anvil 31 and the hammer 35 on the curved portion W-2 of the wire stock W, as above described.

On the next up-stroke of the head H, the rod 41 due to the frictional engagement of the plunger 44 elevates the block 40 thereby through the link 38 rocking the rocker head 33 to cause the hammer 35 to release the formed tongue T. This movement of the head 33 is limited by the engagement of the abutment 33-a on the head 33 with the wall 29-a of the socket 29, and through link 38 the movement of the block 40 is arrested. When the elevation of the rod 41, sliding through the block 40, brings the collar 71 into engagement with the collar 71, the carriage 52 is moved upwardly on its trackway 51 thereby causing the wire stock W to be fed upwardly due to the co-action of the gripper jaw 67 and the plate 68. It is obvious (Figs. 4 and 5) that the means for feeding the wire stock W are so designed and related that the gripper jaw 67 is inoperative on depression of the carriage 52 and is operative on elevation of the carriage 52, and that the degree of travel of the carriage 52 and consequently the degree of feed of the wire stock W are precisely determined by the adjustment of the lock nuts 74 axially of the rod 41. The spring 78 biasing the collar 71 is sufficiently strong to cause the collar 71 to actuate the feeding means under normal conditions and provides a spring-release means in the event of jamming of the wire stock W. The above-described upward feed of the wire stock W provides a precisely measured portion W-1 above the surface 31-a of the anvil 31 to be severed and formed into a tongue T. This portion W-1 projects upwardly beyond the top of the block 23 (Fig. 7). The upward feed of the wire stock W and the step-by-step translating movement of the stock S are so synchronized by the co-action of the feeding means for the wire stock W and the stock S, actuated by the head H, that the opening S-2 in the

stock S is disposed to receive therethrough the curved portion W-2 on the upper end of the portion W-1.

It will be noted (Fig. 1) that after the tongue T has been applied to the body S-5 of the buckle the translating movement of the stock S moved the joined body S-5 and the tongue T, on the first step, to an idle position, and, on the second step, into the bore 25 of the die 1. It will be understood that on the down-stroke of the head H the traction device precisely registers the body S-5 with the punch 24 and the bore 25 so that on completion of the stroke the completed buckle is punched from the stock S and is fed by gravity through the bores 26 and 27 from the apparatus to any suitable container.

Having described my invention, what I claim is:

In an apparatus for forming a buckle tongue from wire stock, and for applying the formed tongue to a buckle body having a pair of openings therein separated by a bar, the combination of a fixed bed; a ram reciprocable relative to said bed; means on said bed and actuated by said ram for so feeding the stock through said bed that its upper end is introduced through one of the openings of the body on said bed; a block on said bed; an anvil formed on said block; a rocker head pivoted on said block for swinging movement toward and from said anvil; a hammer formed on said rocker head, said anvil and hammer being so disposed that said stock is fed therebetween; means connecting said ram and said rocker head for swinging said rocker head by reciprocation of said ram, said anvil and said hammer having co-acting parts whereby when said ram swings said rocker head toward said anvil a precisely measured portion is severed from said stock and formed into the tongue, its upper end being the end of the stock introduced through said opening; and a head on said ram for engaging said end to bend said end downwardly through the other of said openings to attach the tongue to the bar.

EVERYL M. TORBERT.
